UNITED STATES PATENT OFFICE

ALLAN C. AXFORD, OF SAN FRANCISCO, CALIFORNIA

DESIGN FOR A COOKING UTENSIL

Application filed July 14, 1931. Serial No. 40,542. Term of patent 7 years.

To all whom it may concern:

Be it known, that I, ALLAN C. AXFORD, a citizen of the United States, residing at the city and county of San Francisco and State of California, have invented a new, original, and ornamental Design for Cooking Utensils, of which the following is a specification, reference being had to the accompanying drawings forming part thereof:

Fig. 1 is a plan view of a cooking utensil showing my new design.

Fig. 2 is a perspective view of the same.
Fig. 3 is a side elevation view of the same.
I claim:

The ornamental design for a cooking utensil, as shown.

In testimony whereof I have hereunto set my hand this 7th day of July, 1931.

ALLAN C. AXFORD.
